FIG. I

H. O. LLOYD-JONES.

PIPE LINE COUPLING.

APPLICATION FILED AUG. 26, 1910.

1,026,686.

Patented May 21, 1912.

2 SHEETS-SHEET 2.

UNITED STATES PATENT OFFICE.

HORATIO OWEN LLOYD-JONES, OF WINNIPEG, MANITOBA, CANADA.

PIPE-LINE COUPLING.

1,026,686.

Specification of Letters Patent.

Patented May 21, 1912.

Application filed August 26, 1910. Serial No. 579,094.

To all whom it may concern:

Be it known that I, HORATIO OWEN LLOYD-JONES, of the city of Winnipeg, in the Province of Manitoba, Canada, have 5 invented certain new and useful Improvements in Pipe-Line Couplers, of which the following is the specification.

My invention relates to a coupler for effectually interconnecting the train line, the 10 signal line, and the steam heating line in a train of cars, and the object of the invention is to provide an inexpensive, serviceable, and efficient device which will automatically couple and effect a direct interconnection between the several pipe lines 15 of a train of cars, such coupler being constructed so as to make and break coupling quickly, that is, with little sliding contact, so that the wear between the engaging parts 20 is reduced to a minimum.

A still further object is to provide a means for connecting the coupler to the car which will withstand the heavy strains placed on it when the couplers engage.

25 With these and other objects in view which will be more apparent as the description proceeds, the invention consists in the novel arrangement and construction of parts as later described and more particularly 30 pointed out in the appended claims.

Figure 1 represents a side elevation of a portion of two adjoining cars provided with my invention. Fig. 2 represents a plan view of two of my couplers engaged, a portion of 35 the car being shown in dotted outline. Fig. 3 is an enlarged detailed side elevation of one of the couplers, and the coupler supporting means, parts being shown in vertical section. Fig. 4 is an enlarged detailed 40 plan view of one of the coupler heads as it appears when it is disengaged. Fig. 5 is a vertical sectional view through the coupler supporting means, the section being taken in the plane denoted by the line X-X', Fig. 45 3, and looking in the direction indicated by the arrow. Fig. 6 is a vertical sectional view through the movable jaw of the coupling head, the section being taken in the plane denoted by the line Y-Y', and looking 50 in the direction indicated by the arrow.

In the drawings like characters of reference indicate corresponding parts in each figure.

1 and 2 represent a portion of the ends of 55 two adjoining cars of which 3 are the supporting floor beams. 4 and 5 designate the ordinary car couplers for interconnecting

one car with another, and throughout this specification will be referred to as the car couplers. It is to be understood that these 60 form no part of my invention and may be of any approved type. Each car is equipped with a pipe line coupler and supporting means now described.

6 and 7 are brackets securely fastened by 65 bolts to the under side of the car at the ends directly opposite each other, which brackets are supplied with longitudinally extending plates 8.

9 are boxings square in cross section, having 70 the ends 9' and those 9² closed, which boxings are suspended by means of a saddle 10 located at the ends thereof receiving swivel eyes 11 connected by means of pins 12 to lugs 13 dependent from the plates 8. 75 This arrangement is such that it will allow the boxings to swing laterally as well as upwardly and downwardly.

14 are strong spiral springs passing between the free ends of the boxings and the 80 adjoining ends of the plates to which parts they are suitably fastened.

15 are intermediate springs somewhat lighter than those 14, which springs pass between the boxings and the plates midway 85 between the saddles and the points to which the other springs are attached. These springs are also suitably fastened to the respective parts.

16 are shanks passing into the boxings 90 and carrying square pistons or collars 17 which are adapted to slide within the boxings and are supplied with pins 18 at their sides, which pins operate in longitudinally directed slots 19 formed in the sides of the 95 boxings. The shanks slide in suitable bearings formed in the ends 9' and 9² through which they pass. Coiled springs A and B are placed in the boxings surrounding the shank and have their outer ends bearing 100 on the ends 9' 9² of the boxings, and their inner ends engaging with the collars 17 hereinafter referred to on each of the shanks. These springs cushion the shanks.

21 and 22 are two similar engaging heads 105 (right and left), to which are connected the train pipe lines 23, the signal lines 24 and the steam heating lines 25, which lines are formed from flexible piping as is usual.

Each shank 16 is fitted with an outwardly 110 flaring end piece 26 having an open mouth at 27 which is designed to receive the movable jaw of the engaging head shortly described. Each end piece has an opening at

28 adjoining the shank, which opening has its walls converged so as to receive the ends of the jaw. The opening serves the further purpose of allowing ice or other such undesirable material lodging in the end piece to escape when the couplers engage.

29 are more or less wedge-shaped movable jaws pivotally secured by pins 30 to opposing lugs 31 extending from the sides of the 10 end pieces, it being understood that the end pieces are cut away at 26' to admit the jaws. The nose 29' of each jaw is formed with converging sides so that it is adapted to enter snugly the opening 28 in the adjoining head. 15 The outer face 29' of each jaw is concaved so that it will slide easily over the inner face of the opposing end piece when the parts engage, while the heel is supplied with a stop piece or lug 31^a which engages with the 20 end of the shank and prevents the jaw from swinging backwardly farther than is desired. A spiral spring 32 passes between the heel of each jaw and the shank and holds the jaw normally back with the lug 31 engaging with the shank as shown in Fig. 4. The jaws are provided with ducts or 25 passages 33, 34, and 35, which connect up with the pipe lines 23, 24, and 25, respectively. Rubber or soft metal gaskets are placed or 30 screwed into the ends of the ducts 33, 34, and 35 at the points where they open at the inner face of the jaws. The gaskets prevent any leakage occurring in the transmission lines between the heads when the heads 35 are engaged.

In order to better understand my invention I will now describe the manner in which the heads engage assuming at the outset that they are both in the normal position as 40 shown in Fig. 4. As the heads come together the respective jaws pass primarily into the mouths of the respective end pieces and swing on their pivotal pins 30 as the noses slide over the inner faces of the end 45 pieces. When the couplers have finally engaged the noses are in the openings 28 and the gaskets 36 carried by each jaw are pressed closely together so that the pipe lines are connected.

50 I am aware that engaging jaws have already been employed for connecting pipe lines, but find that in any of the types which have come under my notice there is a rubbing contact between the gaskets which is very detrimental as it shortens greatly the life of the same and is very apt to cause leakage. With my coupler it will be noticed that there is practically no rubbing contact between the gaskets as the jaws are not 55 finally forced together until the gaskets are directly opposite each other. Upon cars parting coupling the jaws are pulled apart

60 by the springs 32 so that there is no rubbing contact when they engage or disengage.

What I claim as my invention is:

1. The combination with a suitable supporting means, of a shank carrying an open mouthed end piece, a swingable jaw pivotally secured to the end piece and let in to the side thereof, and a spring pressing the 70 jaw normally, backwardly, as and for the purpose specified.

2. The combination with a suitable supporting means, of a shank carried by the supporting means and provided with an open mouthed end piece, having one of the walls thereof inclined, a wedge-shaped jaw swivelly secured to the end piece and a spring passing between the jaw and the shank, as and for the purpose specified.

75 3. The combination with a suitable supporting means, of a shank carried by the supporting means and provided with an open mouthed end piece having one of the walls thereof inclined toward the shank, a wedge-shaped jaw pivotally secured to the end piece and let in to the side thereof, a spring passing between the jaw and the shank and a lug extending from the jaw and engageable with the shank, as and for 85 the purpose specified.

80 4. The combination with a suitable supporting means, of a shank carried by the supporting means and provided with an open mouthed end piece having an inclined 95 wall, a wedge-shaped jaw pivotally secured to the end piece and let in at the side thereof, said jaw being provided with suitable ducts, gaskets located in the ends of the ducts, a spring passing between the jaw and the shank and a lug extending from the jaw 100 and engageable with the shank, as and for the purpose specified.

5. The combination with a suitable supporting means, of a shank carried by the 105 supporting means and provided with an open mouthed end piece having an inclined inner wall, said end piece being further provided with an opening adjoining the shank having converging walls, a wedge shaped 110 jaw pivotally secured to the end piece and let in to the side thereof, said jaw being provided with suitable ducts and gaskets at the ends of the ducts, a spring passing between the end of the jaw and the shank 115 and a lug extending from the jaw and engageable with the shank, as and for the purpose specified.

Signed at Winnipeg in the Province of Manitoba, this 27th day of June, 1910.

HORATIO OWEN LLOYD-JONES.

In the presence of—
G. S. ROXBURGH,
R. FOSTER.
